UNITED STATES PATENT OFFICE.

CHARLES W. SHEVLIN, OF CHICAGO, ILLINOIS, ASSIGNOR TO CLIMAX CONTAINER COMPANY, OF CHICAGO, ILLINOIS, A CORPORATION OF DELAWARE.

MACHINE FOR IRONING AND FINISHING PARAFFINED CONTAINERS.

1,224,969.

Specification of Letters Patent.

Patented May 8, 1917.

Application filed March 30, 1914. Serial No. 828,212.

To all whom it may concern:

Be it known that I, CHARLES W. SHEVLIN, a citizen of the United States, residing at Chicago, in the county of Cook and State 5 of Illinois, have invented certain new and useful Improvements in Machines for Ironing and Finishing Paraffined Containers, of which the following is a specification.

This invention relates to machines for 10 "ironing" and finishing paraffined paper or strawboard cans and cylindrical receptacles. The object of this invention is to construct a machine of this character that is simple in construction, easy to manipulate, and efficient in its operation. Another object is to 15 provide a machine that will, by its manipulation and treatment of the can, effectively unite the tissues that have been previously paraffined and wound together, so that when 20 the can is finished it will be capable of retaining liquids and oily substances and successfully prevent the same seeping through any portion thereof. Still another object is to provide means that will be capable of 25 moving the receptacle slightly while it is still in contact with the heated mandrel for the purpose of "ironing" the interior surface thereof and producing a smooth surface and effecting the adhering together of the 30 parts of said receptacle.

These and other objects are accomplished by the means and in the manner hereinafter fully described and as more particularly pointed out in the claims, reference being 35 had to the accompanying drawings forming a part hereof, in which—

Figure 1 is a vertical front elevation partly in section of my improved paraffin can finishing machine;

Fig. 2 is a top plan view thereof having the top-plate of the table removed to disclose certain elements below the same;

Fig. 3 is a vertical transverse section taken on line 3—3, Fig. 2;

Fig. 4 is a fragmentary plan view similar to Fig. 2, showing in dotted and full lines two relative movements of the segments of the ironing mandrel and their actuating mechanism;

Fig. 5 is a fragmentary view showing two relative positions of the mechanism for im-

parting the necessary movement to iron the receptacle or can;

Fig. 6 is a detached detail view of one of the heated segments of the ironing mandrel. 55

Referring to the drawings, it will be observed my improved mechanism is supported upon a table or bench comprising suitable side frames or standards A, preferably of cast metal or the like, having upper lateral 60 flanges a to which the bed-plate B is securely bolted. Journaled in suitable alining bearings adjacent one of the vertical edges of each side frame is the master or drive-shaft C, that is preferably disposed in a substantially horizontal plane just below the bed-plate. 65

The central portion of the bed-plate is preferably cut out to form a circular opening 1 therein and a suitable open or skeleton 70 bearing frame 2 is securely bolted to the under face of the bed-plate in such manner that it bridges said opening. Rotatably secured to frame 2 by means of a shouldered smooth-barreled bolt 3 is a suitable rotary 75 reciprocable spider 4 that derives its motion from a horizontally disposed arm 5 secured to and projecting laterally from the under side of said spider. The outer end of this arm extends to and is preferably engaged by a lateral pin 6 on the upper edge 80 of an automatically reciprocable bolt or plunger 7, which latter has its axis substantially parallel to the axis of the master shaft and is provided with a squared portion 85 mounted in alining bearing lugs 8, 8, bolted to the under surface of the bed-plate and has a circular barrel portion that slides in a bearing 9, also pendent from the under side of the bed. Bolt 7 is preferably kept 90

pushed toward one end of its movement by means of a coiled expansion spring 10 disposed around the circular portion of the same between said bearing 9 and a suitable adjustable collar 11 mounted on said bolt 95 substantially as shown in Fig. 1 of the drawings. The opposite end of said bolt is preferably bifurcated as shown at 12, and has a suitable roller 13 journaled between the parallel arms thereof. Said roller rides upon 100 the edge of a face cam 14 mounted on the adjacent portion of the master-shaft C and

from which said bolt derives its reciprocal movement and through the medium of said arm 5 rocks the spider.

The rotary reciprocable spider 4, hereinbefore mentioned, preferably comprises three equidistant arms that radiate from the central boss thereof and at their outer ends said arms are each pivotally connected by suitable horizontally disposed links 15, 15, to the shorter ends of levers 16, 16, that are pivoted mediate their ends to the under face of the bed of the table. The ends of levers 16 opposite links 15 are connected to the lower ends of vertically disposed studs 17 by means of suitable clamp nuts that are screwed onto the lower screw-threaded ends of said studs. Said studs pass through suitable radially elongated slots 17^a, 17^a, and 20^a—20^a, cut respectively into the bed-plate B and the guides 20—20 hereinafter mentioned to accommodate the same, and both the upper and the lower ends of said studs are preferably reduced in diameter to form suitable shoulders (as shown in Fig. 3) that are still further reduced beyond said shoulders to form screw-threaded extensions. The reduced portion of the lower ends of the studs are inserted in longitudinally elongated slots 18, 18, in the adjacent ends of levers 16, while the reduced upper portions of said studs pass through and are secured to the horizontally disposed guide shoes or plates 19, 19, of the mandrel to be hereinafter fully described. Secured in any suitable manner to the top of the bed-plate are several (preferably three) radially disposed guides 20, 20, that are substantially U-shaped in transverse section, having the longitudinal edges of the parallel members slightly undercut as shown in Fig. 1, so as to guide the shoes 19 and guard against their accidental removal therefrom. These shoes are substantially flat, rectangular-shaped plates having their longitudinal side edges beveled slightly to fit the undercut of the guides. Alternating between the guides above mentioned are an additional set of radial guides 20^a, 20^a, constructed in a manner similar to guides 20 and in which are mounted suitable shoes 19^a, 19^a, that are likewise similar in construction to shoes 19 hereinbefore mentioned. Shoes 19^a, however, are kept pushed toward the inner limit of their movement by means of suitable longitudinally-disposed spindles 21, 21, secured to and projecting outwardly from the outer edges of said shoes, and which have their outer portions slidably journaled in substantially L-shaped bearing lugs 22, 22, secured to and projecting from the bed B of the table. Coiled expansion springs 23, 23, surround said spindles between the inner faces of said lugs and the outer edges of said shoes so as to force the latter inwardly in their respective guides as will be understood. These two sets of shoes

afford a suitable means for mounting the mandrel of the machine, which is preferably arranged as follows: Suitable vertically-disposed hollow members 24, 24, are mounted upon and carried by the inner ends of shoes 19^a, said members being segmental shaped in horizontal section, the arc of the same being struck from the pivotal center of the spider above described and the vertical end walls thereof converging toward each other 75 at an obtuse angle as shown at 24^a in Figs. 2 and 4 of the drawings. Disposed between the hollow segmental mandrel members and preferably in contact with the angular end walls 24^a thereof are suitable vertically disposed wedge members 25, 25, that are mounted upon and arise from the inner end edges of the shoes 19. Said wedge members are preferably solid and the faces thereof that contact with the adjacent angular faces 85 of the hollow members preferably converge outwardly as shown, so as to present the flat surface thereof to the same. The outer surfaces of the wedge members are preferably segmental shaped so that when the wedges 90 and mandrel members are in the position shown in Fig. 2 of the drawing the outer circumference of all of said parts will form a continuous curved surface.

Under normal conditions the positions of 95 the segmental members of the mandrel are substantially as illustrated in Fig. 4, with the wedges and the segmental sections at the limit of their inward movement. In this position the paper tube, can, or other receptacle having been previously formed by rolling paraffin-impregnated tissue is dropped over the mandrel. The revolving cam 14, by reciprocating the plunger 7, swings arm 5 and rotates the spider 4, which latter transmits its motion through links 15 to levers 16 and forces the shoes 19 to move in an outward radial direction. The wedge members 25 of the mandrel which are mounted on these shoes exert their force against springs 110 23 by their pressure against the segmental members 24 of the mandrel. This concerted movement of the several elements of the mandrel causes the same to expand sufficiently to engage and firmly press against 115 the interior surface of the can or receptacle. Heat is imparted to the hollow segmental members 24 of the mandrel by admitting a heated fluid through an inlet pipe 26 and discharging it therefrom through exhaust 120 pipe 27, and thus keeps the segmental members hot enough to melt the paraffin on the receptacle and cause the several layers of tissue to unite and knit or seal them firmly together.

In order to finish the receptacle with a smooth interior surface it has been found expedient to "iron" or move the same slightly upon the mandrel in either a rotary or a vertical direction. I prefer, however, 130

to "iron" the receptacle by raising it vertically upon the mandrel and ejecting it at the same time, thus eliminating an operation and saving time. Surrounding the hollow 5 segmental mandrel members is a corresponding number of horizontally disposed ring segments 30, 30, that rest upon the upper surface of the guides 20 and 20^a as shown. These ring segments have horizontal motion 10 and they are adapted to be raised vertically parallel to the sides of the mandrel by the vertical reciprocation of vertically disposed rods 31, 31, that pass through openings in the guides and table and have their lower 15 ends mounted in suitable holders 32, carried on the ends of brackets 33 radiating from a central boss 34. Said boss 34 is secured to and carried by the upper end of a vertically disposed, longitudinally reciprocal 20 plunger 35 that has bearings 36, 36^a, in the upper and lower angles of a diamond shaped frame 37 having its opposite corners mounted upon suitable lugs or shoulders 38 projecting inwardly from the adjacent portion 25 of the side frames A.

I prefer to employ the following means in order to give the plunger 35 the proper reciprocation:—A suitable eccentric cam 39 is mounted on the end of shaft C (opposite 30 cam 14) and engaging the same is an anti-friction roller 40 that is journaled on the upper bifurcated end of a second-class lever 41 fulcrumed in a lateral embossment A' of the side frame. A horizontally disposed 35 rock-shaft 42 is journaled in said side-frame just below the horizontal plane of the lower end of said lever and said shaft carries a long and a short arm 43 and 44 respectively. The shorter arm 44 is connected by a link 40 45 to the lower end of lever 41 while the longer arm is provided with a longitudinally elongated bearing slot 43^a in which the spindle of an anti-friction roller 46 is mounted. Journaled in bearing brackets 45 47 secured to the outer surface of the side-frame is a horizontally disposed rock shaft 47^a which mediate its ends carries a substantially horizontally disposed lever 48 that rests mediate its ends upon and is actuated 50 by the roller 46 and has its opposite bifurcated end provided with slots 48^a through which a horizontal pin α , tapped into the adjacent end of plunger 35, is adapted to pass. Thus it will be seen that the operation 55 of cam 39 moves lever 41 and the latter through its link 45 rocks shaft 42 on which arm 43 is secured. This causes the lever 48 to be raised and it in turn elevates plunger 35 in its bearings so that the segments of 60 the ring 30 will be raised by their respective rods sufficiently to eject the can or receptacle off the upper end of the mandrel. As before mentioned, this raising of the receptacle while upon the heated mandrel is sufficient 65 to "iron" the interior surface of the

cam and finish the same smoothly as well as cause the removal of the finished article.

In order to suitably adjust the relative movement of lever 48 and the resulting elevation of the ring segments 30 I prefer to 70 lock the spindle of roller 46 in various adjusted positions in slot 43^a by means of a lock-nut 49 screwed on the extended screw-threaded end of said spindle.

What I claim as new and desire to secure 75 by Letters Patent is:

1. In a device of the kind specified, a sectional mandrel upon which a hollow receptacle is adapted to be retained, means for expanding said mandrel into contact with 80 said receptacle, and a device substantially surrounding said mandrel for moving said receptacle with respect to said mandrel while the latter is in contact therewith and expanded. 85

2. A device of the kind specified, comprising an expansible mandrel upon which a hollow receptacle is adapted to be retained, means for expanding and contracting said mandrel into and out of contact with said 90 hollow receptacle, and an ejector comprising a plurality of segmental plates surrounding said mandrel and against which said mandrel is expanded, said ejector adapted to be operated while said mandrel 95 is in an expanded position.

3. A device of the kind specified, comprising a mandrel upon which a hollow receptacle is adapted to be retained, consisting of a plurality of segmental sections, a 100 plurality of wedge members interposed between said segmental sections, a corresponding number of radially disposed reciprocable carriers upon which said segmental sections and wedge members are respectively mounted, and devices for forcing said wedge members against said segmental sections to expand said mandrel into contact with said hollow receptacle. 105

4. A device of the kind specified, comprising a mandrel upon which a hollow receptacle is adapted to be retained, consisting of a plurality of returnable segmental sections, a plurality of wedge members interposed between said segmental sections, a 110 corresponding number of radially disposed reciprocable carriers upon which said segmental sections and wedge members are respectively mounted, and devices for forcing said wedge members against said segmental sections to expand said mandrel into contact with the walls of said receptacle. 115

5. A device of the kind specified, comprising a mandrel upon which a hollow receptacle is adapted to be retained, consisting of a plurality of segmental sections, a 120 plurality of wedge members interposed between said segmental sections, a corresponding number of radially reciprocable carriers upon which said segmental sections and 125

wedge members are mounted, devices for forcing said wedge members against said segmental sections to expand said mandrel, and means for automatically returning said 5 segmental sections to normal position.

6. A device of the kind specified, comprising a suitable support, a contractible sectional mandrel mounted thereon, and means for expanding said mandrel comprising 10 a plurality of wedges engaging the sections thereof, shoes upon which said wedges are carried, levers each having one end engaging one of said shoes, a rotary reciprocable spider to which the opposite ends 15 of said levers are connected, and means imparting motion to said spider.

7. A device of the kind specified, comprising a suitable support, a mandrel mounted thereon upon which a hollow receptacle is adapted to be retained, means for 20 moving the receptacle with relation to said mandrel comprising a plurality of ring segments surrounding said mandrel, a plurality of vertically reciprocable plungers upon 25 which each one of said ring segments is separately mounted, and devices for reciprocating said plungers.

8. A device of the kind specified, comprising a suitable support, a mandrel mounted thereon that is capable of expansion and contraction, means for moving the article operated upon by the mandrel that comprises a plurality of ring segments surrounding said mandrel, vertically reciprocable plungers on which said ring segments are mounted, devices for reciprocating said plungers, a frame below and in axial alignment with the axis of said mandrel to which the lower ends of said plungers are connected, a reciprocable shaft upon which said frame is carried, and devices for reciprocating said shaft.

9. A device of the kind specified, comprising a suitable support, a mandrel

mounted thereon that is capable of expansion and contraction, means for moving the article operated upon by the mandrel that comprises a plurality of ring segments surrounding said mandrel, vertically reciprocable plungers on which said ring segments are mounted, devices for reciprocating said plungers, and means for adjusting the movement of said plungers.

10. In a device of the kind specified, a sectional heated mandrel over which a hollow receptacle is adapted to be mounted, means for expanding said mandrel into contact with said receptacle, and devices for moving the receptacle with respect to said mandrel while the latter is in its expanded position and frictionally contacting the walls of the receptacle.

11. A forming member, means for expanding said member and causing the same to engage an article and shape it to conform to the forming member, and means for causing a movement between the article and the member while the latter is expanded and in engagement with the article.

12. A forming member, means for expanding said member and causing the same to engage an article and shape it to conform to the forming member, a means for causing the movement of the article while in engagement with said member and while the latter is expanded.

13. An ironing machine comprising a heated holding mandrel, means for expanding said mandrel and causing the same to engage an article to be ironed, and means for causing a relative movement between the article and mandrel while the latter remains expanded and in frictional engagement with the former.

CHARLES W. SHEVLIN.
